VARIABLE SELECTIVITY CIRCUITS

Bernardus W. van Ingen Schenau, Eindhoven, Netherlands, assignor, by mesne assignments, to Radio Corporation of America, New York, N. Y., a corporation of Delaware

Application October 15, 1937, Serial No. 169,119
In Germany December 3, 1936

6 Claims. (Cl. 178—44)

This invention relates to a radio receiving arrangement with variable selectivity, and has for its object to provide means which allow of controlling either manually or automatically the selectivity in an extremely simple manner.

According to the invention in a radio receiving arrangement comprising one or more tuned oscillatory circuits one or more conductors are provided which are inserted in at least one of the oscillatory circuits and whose resistance is strongly dependent on the temperature, so that this resistance varies under the influence of the received high, or intermediate, frequency oscillations and/or of a direct current or alternating current of any desired frequency supplied to the said conductors, and a variation of the damping of the oscillatory circuits and/or of the mutual coupling of at least two of the oscillatory circuits is brought about.

10 The conductors whose resistance is strongly dependent on the temperature are preferably constituted by incandescent lamps of the kind used in electric pocket lamps. These incandescent lamps have a very small resistance in the cold state, whereas the resistance in the hot state is appreciably higher. With a 4 volts incandescent lamp of 160 mw. for instance, a resistance of about 10 ohms was measured in the cold state, whereas the resistance had a value of about 100 ohms in the hot state. These incandescent lamps have the advantages of a very low price and of a very small self-capacity, so that the filament may be heated by means of the received radio, or intermediate, frequency oscillations and a 20 separate supply for selectivity-control can be dispensed with.

25 The invention is not limited to the use of pocket lamp bulbs, but includes also the use in the said way of other conductors whose resistance is strongly dependent on the temperature. It is also possible, for instance, to use conductors whose resistance decreases with increasing temperature.

30 The invention will be more clearly understood by reference to the accompanying drawing representing, by way of example, several modifications in Figs. 1 to 6 thereof.

35 The simplest form of construction of the invention is represented in Fig. 1 which shows an oscillatory circuit comprising an inductance coil L and a condenser C and forming part of the radio, or intermediate, frequency amplifier of a radio receiving circuit arrangement. An incandescent lamp G is connected in series with the condenser C. Since the incandescent lamp G has a very low self-capacity the radio, or inter-

mediate, frequency current will traverse the filament of the incandescent lamp. Upon receiving a weak signal the filament remains cold and the damping brought about by the incandescent lamp may be neglected. If, on the contrary, a strong signal comes in the temperature of the filament will increase which involves an increase of the resistance so that the oscillatory circuit will be damped to a larger extent and the selectivity of the receiving arrangement will decrease. In 10 this way automatic control of the selectivity in accordance with the amplitude of the incoming signal is assured so that the selectivity decreases with increasing amplitude of the received signal.

15 Fig. 2 shows a band-pass filter which forms part of the radio, or intermediate, frequency amplifier of a radio receiving arrangement, and comprises two inductively coupled oscillatory circuits L₁, C₁ and L₂, C₂. Each circuit comprises an incandescent lamp G₁ and G₂ respectively connected in series with the tuning condenser. With an increase of the received signal the two oscillatory circuits are damped to a higher extent, which involves an increase of the width of the transmitted frequency band.

20 Fig. 3 represents a circuit arrangement in which the mutual coupling of two oscillatory circuits is controlled automatically. For this purpose an incandescent lamp G is connected in parallel with the coupling condenser C₃. With a small amplitude of the incoming signal the incandescent lamp has a low resistance so that the coupling condenser C₃ is substantially short-circuited and the mutual coupling of the two circuits is weak. With an increase of the amplitude of the received signal the current traversing the incandescent lamp will also increase. The resistance connected in parallel with the coupling condenser will consequently increase due to which the coupling between the two circuits becomes closer, and the 25 width of the transmitted frequency band is increased.

30 In the above described arrangements the heating of the filament was effected by the received radio, or intermediate, frequency oscillations. This method of heating generally requires, however, a comparatively strong current, so that the circuit including the incandescent lamp must be preceded by one, or more, amplifying stages to secure perfect selectivity control. For these 35 amplifying stages, no, or only a very small, automatic gain control could be used, since in using a strong automatic gain control a substantially constant signal would be always supplied to the tube so that no selectivity control would be 40 45 50 55

achieved. Moreover, the circuit arrangements referred to allow automatic control of the selectivity only in accordance with the intensity of the received signal, whereas a control in accordance with the intensity of one or more signals having an adjacent frequency is generally to be preferred. These disadvantages are avoided in the arrangements represented in Figs. 4 and 5 in which a separate control voltage is passed through to the incandescent lamps. This control voltage may be either a direct current voltage; or an alternating voltage having any desired frequency, for instance an alternating voltage derived from the power mains, since due to the high inertia of the incandescent lamps there is no risk of modulation of the signal by the frequency of the control voltage. The latter may be varied either by hand, or automatically. Automatic selectivity control can be obtained by supplying to the incandescent lamps a direct current voltage depending on the intensity of the received signal, and/or on the intensity of one or more signals having an adjacent frequency. A direct influencing of the resistance of the incandescent lamps by the received signal can be avoided, if desired, by giving the control voltage a high value with respect to the amplitude of the signal occurring in the circuit, for instance, by effecting the selectivity control in an oscillatory circuit in which the received signal has still a small amplitude.

The circuit arrangement shown in Fig. 4 corresponds to that represented in Fig. 1, but with the difference that the incandescent lamp G is supplied with a separate control voltage E_r through the resistance R . In the same manner the arrangement shown in Fig. 5 corresponds to that illustrated in Fig. 3.

The circuit arrangements represented in Figs. 3 and 5, wherein the width of the frequency band transmitted by a band-pass filter is controlled by a modification of the coupling of the band-pass filter circuits, have the drawback that the middle of the transmitted frequency band is shifted by the control, and, moreover, the response curve of the band-pass filter is unsymmetrical. In fact the resonance frequencies of the band-pass filter are determined on the one hand by the natural frequency of the circuit $L_1 C_1 C_2 L_2$, and on the other hand by the natural frequency of the circuits $L_1 C_1 C_3$ and $L_2 C_1 C_3$. The effective capacity in the two last-mentioned circuits is altered upon controlling the band width, due to which one of the resonance frequencies is shifted, whereas the other resonance frequency remains unaltered. Moreover, the circuits $L_1 C_1 C_3$ and $L_2 C_1 C_3$ receive an additional damping due to which the resonance frequency determined by these circuits is damped to a higher extent than the other resonance frequency, so that the response curve becomes unsymmetrical.

These drawbacks are avoided by using the arrangement represented in Fig. 6. This figure shows a band-pass filter comprising two mutual coupled tuned circuits $L_1 C_1 C_4$ and $L_2 C_2 C_5$ in which an incandescent lamp G_1 and G_2 respectively is connected in parallel with the coupling condensers C_4 and C_5 respectively. The junction point of the condensers C_1 and C_4 is connected to the junction point of the condensers C_2 and C_5 through an inductance coil L_3 which is connected in parallel with an incandescent lamp G_3 . The control voltage E_r is supplied to the series-connection of the incandescent lamps G_1 , G_3 and G_2

through the resistance R . The large condensers C_6 and C_7 serve to prevent a short-circuit of the control voltage and a supply of control voltage to the amplifying tube succeeding the band-pass filter.

With an increase of the control voltage the resistance of the three incandescent lamps increases to the same extent. This involves a decrease of the effective capacity in the circuits $L_1 C_1 C_4$ and $L_2 C_2 C_5$, whereas the effective self-inductance in the circuit $L_1 C_1 L_3 C_2 L_2$ increases. By giving the inductance L_3 a proper value the two resonance frequencies of the band-pass filters are shifted in an opposite direction by the same distance during the control operation, so that the middle of the transmitted frequency band remains unaltered. In this case the resistance of the incandescent lamp G_3 is given such a value that the circuit $L_1 C_1 L_3 C_2 L_2$ is damped to the same extent as the circuits $L_1 C_1 C_4$ and $L_2 C_2 C_5$ so that a symmetrical response curve is obtained.

What is claimed is:

1. In combination, a pair of tuned circuits, each circuit comprising an inductive reactance, a capacitive reactance and a coupling reactance, a temperature-dependent resistance element connected across each coupling reactance, an auxiliary reactance of opposite sign to said coupling reactances operatively associated with the latter, a third temperature-dependent resistance element connected across the auxiliary reactance, and means for varying the temperature of said elements.

2. In combination, a pair of tuned circuits, each circuit comprising an inductive reactance, a capacitive reactance and a coupling reactance, a temperature-dependent resistance element connected across each coupling reactance, an auxiliary reactance of opposite sign to said coupling reactances operatively associated with the latter, a third temperature-dependent resistance element connected across the auxiliary reactance, means for varying the temperature of said elements, and each of said resistance elements consisting of an incandescent lamp.

3. In combination, a pair of tuned circuits, each circuit comprising an inductive reactance, a capacitive reactance and a coupling reactance, a temperature-dependent resistance element connected across each coupling reactance, an auxiliary reactance of opposite sign to said coupling reactances operatively associated with the latter, a third temperature-dependent resistance element connected across the auxiliary reactance, said resistance elements each consisting of an incandescent lamp, and the filaments of the lamps being in series relation, and means for varying the temperature of said elements.

4. In combination, a pair of tuned circuits, each circuit comprising an inductive reactance, a capacitive reactance and a coupling reactance, a temperature-dependent resistance element connected across each coupling reactance, an auxiliary reactance of opposite sign to said coupling reactances operatively associated with the latter, a third temperature-dependent resistance element connected across the auxiliary reactance, means for varying the temperature of said elements, each of said coupling reactances being a condenser, and said resistance elements being in series with said varying means.

5. In a radio circuit, a tuned circuit including a coil in shunt with a condenser, an incandescent lamp having its filament in series relation with

5 said condenser and coil, means for varying the temperature of the filament with current derived from radio signals thereby to adjust the filament resistance, a second tuned circuit of the same frequency as the first tuned circuit, a coupling reactance between the two tuned circuits, and said filament being in shunt with the reactance.

6. In combination, in a band pass network, a pair of tuned circuits, each circuit including a

coil, a tuning condenser and a coupling condenser, a temperature-dependent resistance element connected across each coupling condenser, an inductive reactance connected between one pair of like terminals of said resistance elements, 5 a third temperature-dependent resistance element being across the reactance, and means for varying the temperature of said elements.
